UNITED STATES PATENT OFFICE.

SARAH G. NOLAN, OF WASHINGTON, DISTRICT OF COLUMBIA.

SHOE-FASTENER.

1,189,993.

Specification of Letters Patent.

Patented July 4, 1916.

Application filed February 24, 1915. Serial No. 10,295.

To all whom it may concern:

Be it known that I, SARAH G. NOLAN, a citizen of the United States, residing at Washington, in the District of Columbia, 5 have invented certain new and useful Improvements in Shoe-Fasteners; and I do hereby declare the following to be a full, clear, and exact description of the invention, such as will enable others skilled in the art 10 to which it appertains to make and use the same.

This invention relates to shoe fasteners of the hinged-button variety, and has for an object to provide a button hinged to an arm 15 which in turn is hinged to the shoe in such manner and position as to eliminate the necessity of a button-hook in buttoning the shoe.

A further object of the invention is to 20 provide an arm hinged to the shoe swinging in a plane toward and from the button-hole with a button hinged on the end of the arm, pivoted to swing about the arm as an axis.

With these and other objects in view, the 25 invention consists in certain features of construction, combination and arrangement of parts as will be hereinafter more fully described and claimed.

In the drawings:—Figure 1 is a perspective view of a shoe showing the application 30 of the present invention thereto. Fig. 2 is a perspective enlarged view of the article removed from the shoe. Fig. 3 is a detail view showing the position of the parts as 35 the button first enters the button-hole. Fig. 4 is a detail view of the parts in the second position after being entered in the button-hole. Fig. 5 is a detail view of the parts in the third position after entering the button- 40 hole—that is to say, with the button turned down upon the arm. Fig. 6 is a detail view showing the position of the parts in operative or wearing condition. Fig. 7 is an enlarged detail sectional view showing the 45 manner of hinging the arm to the head. Fig. 8 is a detail perspective view of a modified form of hinging the arm to the shoe.

Like reference characters designate corresponding parts throughout the several 50 views.

The improved fastener which forms the subject-matter of this application comprises an arm 10 hinged to the shoe along the flap 55 opposite to that having the button-holes, such hinging being accomplished in the preferred form by employing a hinge member

11 having prongs 12 thereon capable of being inserted through the material of the shoe and folded or clenched down as shown at 13 in Figs. 3 to 6 inclusive.

Instead of employing the hinged member 11 with prongs 12 a staple 14 as shown at Fig. 8 may be employed to hinge the arm 10 to the shoe. Whatever the manner employed for hinging the arm to the shoe, it is 65 desirable that the arm swing in a plane which passes through the length of the button hole, and as illustrated herewith such plane is horizontal. The other or outer end of the arm is bent at approximately right 70 angles into a rigid foot 15 standing in said horizontal plane, so that as viewed from above the arm is substantially L-shaped; and across the outer end of this foot a button-head 16 is hinged thereto on a line sub- 75 stantially parallel with the length of the arm, whereby the head is permitted movements in a vertical plane. This hinging may be accomplished in any approved manner, but by preference the outer end of the foot 80 15 is turned down into a toe 19 whose extremity has a squared pintle 17 rigidly engaging the head 16 and bearing on a spring 18 therein, whereby said head is yieldingly held in either of two positions. When it 85 stands horizontal it underlies the arm as seen in Figs. 3 and 4, and when it is vertical it stands alongside the arm and to what might be called the rear thereof as seen in Figs. 5 and 6.

In operation, the fasteners corresponding to the number of button-holes in the shoe are secured to the flap of the shoe opposite to that having the button-holes in such position that when the button-heads 16 are in 95 proper position in the button-holes, the shoe will be made to fit the foot of the wearer all in the usual and well-known manner. The shoe is buttoned by turning the button-head to the position shown at Figs. 1 and 2—100 that is to say, with the head substantially horizontal—and swinging the arm forward as shown at Fig. 3 and the second button from the top at Fig. 1. In this position the button-head is properly located to pass 105 through the button-hole without spreading the hole, or requiring the use of a button-hook. The button is now passed through the button-hole the arm is then swung outward to the position shown at Fig. 4, and the top 110 button at Fig. 1, which serves to raise the button-head some distance above the surface

of the flap of the shoe. The button head is now turned on its hinge 17 to a vertical position as shown at Fig. 5. Having turned the button to this position, the device is permitted to be drawn by the tension of the shoe back to a normal or wearing position as shown at Fig. 6, and the lower button at Fig. 1, when the appearance of the shoe is exactly the same as the appearance of any 10 buttoned shoe.

In unbuttoning the shoe, it is obvious that the above method will be reversed—that is to say, the device in the position shown at Fig. 6 will be moved back upon the pivot of its arm to the position shown at Fig. 5, the button-head then turned down to the horizontal position shown at Fig. 4, and finally the parts permitted to assume the position shown at Fig. 3 when the flap may be easily 20 lifted off from the button head without resistance.

What I claim is:

1. A button fastener comprising an arm 25 bent at one end into a foot and the latter bent at right angles to the first bend into a toe, a hinge at the inner end of the arm permitting it to swing in a given plane, a head, a pintle at the outer end of said toe pivotally engaging the head and permitting the latter 30 to swing in a plane at right angles to that mentioned, and a spring in the head engaging said pintle.

2. A shoe fastener comprising an arm adapted to be hinged at one end to the shoe 35 so as to swing in a given plane and having

its other end bent at an angle into a foot standing in said plane, the foot being bent at right angles into a toe and the latter at its outer extremity having a square pintle, a button head hingedly mounted on said 40 pintle to swing in a plane at right angles to that mentioned, and a spring in said head for holding it in either plane.

3. A shoe fastener comprising an arm provided with a hinge at one end adapting it to 45 swing in a given plane and having its other end bent at right angles into a foot standing in said plane, the foot being bent at its outer end into a toe, and a head hingedly mounted on the toe so as to swing from a position at 50 right angles to the toe to a position alongside the toe and arm.

4. A shoe fastener comprising an arm provided with means at one end adapting it to swing in a given plane and having its other 55 end bent at right angles into a foot standing in said plane, the foot being bent at its outer end into a toe, an angular pintle across the extremity of said toe, a button-head hingedly mounted on the pintle of the toe so as to 60 swing around the arm in a plane at right angles to that mentioned, and yielding means in the head engaging said pintle for holding the head in either of two positions.

In testimony whereof I affix my signature 65 in presence of two witnesses.

SARAH G. NOLAN.
